FURNITURE CONSTRUCTION

Leopold Stickley, Fayetteville, N. Y.

Application April 15, 1937, Serial No. 137,085

1 Claim. (Cl. 45—77)

This invention relates in general to furniture construction, and more particularly to the construction of articles of furniture equipped with drawers, such as desks, bureaus, chest of drawers etc.

The invention has as an object a construction by which the drawer is guided, during sliding movement thereof, in such manner that the drawer will not bind and accordingly, may be moved inwardly and outwardly by grasping the drawer at any point along the front side thereof.

The invention has as a further object, a construction by which the drawer is maintained in substantially horizontal position during sliding movement thereof, and by which the drawer is accurately fitted to the framework with no perceptible play between the drawer and the framework, and by which construction the drawer will not become bound in the framework because of change in atmospheric conditions.

The invention consists in the novel features and in the combinations and constructions hereinafter set forth and claimed.

In describing this invention, reference is had to the accompanying drawings in which like characters designate corresponding parts in all the views.

Figure 1 is a plan view of a drawer and contiguous portion of the framework with parts shown in section.

Figure 2 is a view taken on line 2—2, Figure 1.

Figure 3 is a view taken on line 3—3, Figure 2.

Figure 4 is a front, elevational view of the drawer and contiguous portion of the framework with parts shown in section.

Figure 5 is a fragmentary, plan view of one rear corner of the drawer illustrating a modified form of guide member.

Figure 6 is a fragmentary, elevational view of the structure shown in Figure 5.

Figure 7 is a fragmentary, front elevational view of the drawer receiving framework and contiguous portion of the drawer with parts shown in section and illustrating a modified form of the lateral guide member.

It is well appreciated by those familiar with the art of constructing furniture that the use of drawers creates a considerable problem. This is particularly true in the construction of the better grades of furniture where the entire article is formed of wood. Due to the inherent characteristic of wood changing in dimension because of change in atmospheric conditions, difficulty is encountered in manufacturing an article equipped with sliding drawers. If the drawers are ac-

curately and properly fitted into the drawer receiving framework at the furniture manufacturing plant, the drawers will bind and stick during damp weather. The greatest trouble is encountered by the drawer sticking along the top and bottom edges of the sides of the drawer. This is due to the fact that wood swells and shrinks crosswise of the grain, and does not change to any noticeable extent lengthwise, or with the grain. To overcome this difficulty, it is conventional practice to so construct the drawer and fit the same to the framework with an appreciable amount of clearance between the drawer and the framework, the clearance being sufficient to allow the wood to expand and swell without binding in the framework. However, when the article of furniture so constructed is used in an ordinary or dry atmosphere, the drawer is extremely loose in the framework and the front of the drawer sags or drops downward when the drawer is pulled out.

The feature of this invention is to so construct the drawer and framework that there is a small amount of clearance between the drawer and the framework, whereby the drawer properly fits the framework and will not sag when it is drawn outwardly, and at the same time the drawer will not bind or stick in damp atmospheric conditions. The framework may be of any suitable size or construction, depending upon the type of article it is incorporated in.

For convenience of illustration, the framework herein disclosed includes vertical side members 10 and a rear wall 11. The side members 10 are formed with dove-tail slots extending from the rear wall 11 forwardly to a point adjacent the front of the framework. Drawer supporting rails 12 are arranged in these slots and extend from the rear wall 11 forwardly to a front cross rail 13, the ends of which are also located in the slots in the side 10. The drawer is slidably mounted in the opening between the side rails 12 and cross rails 13, and consists of a front end member 14, a rear end member 15, and side members 16, and a bottom 17. The drawer illustrated is of conventional construction. The sides and end pieces are formed with a rabbet spaced apart from their lower edges to receive the peripheral margin of the bottom 17. It will be understood that the sides 16 of the drawer are slidably mounted upon the rails 12, and the top edges of the sides 16 usually coact with the supporting rails of the drawer above to prevent the drawer from tilting when pulled outward.

In order that the drawer may slide freely, it is

necessary that it be guided both laterally and vertically. Heretofore, it has been conventional practice to rely upon the sides 16 of the drawer coacting with the sides of the framework 10 for 5 lateral guidance. In such construction, if the drawer is grasped at one forward corner, or the drawer is of appreciable length and provided with a pair of spaced apart handles, and one handle only is pulled, the drawer becomes canted 10 with one side thereof engaging one side of the framework adjacent the front thereof, and the rear portion of the opposite side of the drawer engaging the opposite side of the framework at the rear thereof, with the result that it is necessary to apply considerable effort to pull the drawer 15 out, or push the same back in place.

This invention has to do in part with a particularly novel construction for laterally guiding the drawer, and by which the drawer will not become 20 canted, and by which the drawer is freely slideable regardless of the load carried thereby, or whether the force is being applied in the center or at one end of the front side of the drawer.

This guide means is here shown in the nature 25 of a pair of guide strips 18 mounted upon the supporting rails 12 and yieldingly pressed against the inner surface of the side members 16 below the bottom members 17. Preferably, the guide strips 18 are pivotally mounted between their 30 ends to the supporting rails 12, as by screws 19. The lateral guide strips 18 are mounted on the rails 12 in spaced apart relationship to the inner surface of the sides 10 of the framework, the spacing being such as to receive the lower edges 35 of the drawer side 16. The guide strips 18 and rails 12 are provided with counterbores 20, 21, respectively to receive the coiled portion of a torsion spring 22, one end of which is arranged in a slot 23 formed on the upper surface of the 40 rail 12, and the opposite end of the spring is arranged in a slot 24 formed in the under surface of the guide strip 18. The guide strip 18 is also formed with an enlarged aperture 25, through which the screws 19 extend.

The arrangement of the spring 22 is such as 45 to effect yielding movement of the strip 18 throughout its entire length toward the inner surface of the drawer sides 16, and to particularly move the guide strip about the pivot screw 19 to urge the outer ends of the guide strips toward the walls 10 of the framework.

It will be observed that it is not necessary to cut any notches in the front of the framework or drawer in connection with the guide strips 18. 50 The forward ends 26 of the guide strips are tapered, as at 28, so that the drawer may be readily and conveniently inserted in the framework.

In operation, the rear ends of the sides 16 of the drawer coact with the tapered surfaces 28 and 55 move the forward ends 26 of the lateral guide strips 18 inwardly, or toward each other, whereby the drawer may be pushed inwardly with the lower edges of the sides 16 overlapping the outer edges of the guide strips 18, and the guide strips 18 are yieldingly pressed against the inner surfaces of the sides 16, as previously described. Accordingly, any tendency of the drawer to 60 become canted is resisted in both directions by the action of the springs 22.

70 It will be observed that with this lateral guide construction, the drawer is yieldingly maintained in parallel relationship with the framework, with the result that the drawer is freely slideable in the framework.

75 This invention further includes means for

guiding the drawer vertically, or for maintaining the drawer in horizontal position during sliding movement of the same. The sides 16 and the rear wall 15 of the drawer are slightly less in width than the front pieces 14. The clearance between the upper edge of the sides 16 and the rail 12 above is sufficient to accommodate for any expansion or swelling of the sides 16, because of atmospheric changes.

With this construction, it is obvious that when 10 the drawer is pulled out, the forward end will drop or tilt downwardly until the rear end of the upper edge of the sides 16 coacts with the under side of the rails 12 above.

I provide means to prevent this tilting in the 15 nature of vertically arranged guide pieces 30. In keeping with the remainder of the structure, the guide pieces 30 are also formed of wood and are mounted on the inner surface of each side 20 16 of the drawer adjacent the rear end thereof, and with the grain extending vertically or transversely of the sides 16. The guide pieces are of such length that when they rest upon the bottom 25 17 they project upwardly from the upper edge of the sides of the drawer and terminate adjacent the under side of the rails 12 above, there being a slight clearance between the upper ends of the guide pieces 30 and the rails 12 to permit free sliding movement of the drawer.

Due to the fact that the grain of the guide 30 pieces 30 extends transversely of the drawer side 16, or vertically, these pieces will not change in length with atmospheric changes and accordingly, the clearance between the upper ends of the 35 guide pieces 30 and the rails 12 above will not vary. Accordingly, the drawer is maintained in substantially horizontal position at all times during sliding movement of the drawer. Due to the fact that the side members 16 of the drawer will 40 swell and expand an appreciable amount, the 45 guide pieces 30 are secured to the side members 16 in such manner that the side pieces of the drawer are free to expand or swell without effecting vertical movement of the guide pieces.

Referring to Figures 1 to 4, the inner surfaces 45 of the drawer sides 16 are formed with transversely extending dovetail slots, and the guide pieces 30 are provided with complementary dovetail ribs of slightly less width than the slots. That is, the guide pieces 30 are slidably mounted 50 in the slots in the sides of the drawer. The guide pieces 30 may be secured at their lower ends to the drawer by being glued to the bottom 17, or by a screw 31 extending through the bottom 17 into the lower end of the guide piece 30.

55 In Figures 5 and 6, the guide pieces 30 are arranged in the rear corners of the drawer, and are secured to the side members 16 thereof so as to permit the side members to swell and shrink without effecting movement of the guide pieces. 60 As here shown, the guide pieces 30 are formed with vertical slots 32 through which a screw 33 extends, and which is threaded or screwed into the side member 16. Pivotal movement of the 65 guide member 30 about the screw 32 is prevented by contact of the guide members with the rear end member 15 of the drawer.

If desired, the projecting or upper ends of the guide pieces 30 may also be used as part of a lateral guide mechanism for smaller drawers 70 which have a small load carrying capacity, and which are not likely to become canted. This guide structure comprises a guide piece 35 mounted on the under side of the rail 12 above the drawer and coacts with the inner surface or 75

sides of the guide piece 30. The guide strips 35 are provided with one or more enlarged holes to receive screws 36. The screws 36 are located in the rails 12 to approximately position the 5 guide strips 35, and the guide strips subsequently adjusted toward or from the side members of the drawer, and the screws 36 then tightened to secure the guide strip in adjusted position.

The guide strips 18 may also serve as a stop to 10 limit the inward movement of the drawer. Preferably however, the outer or front ends of the guide strips 18 are provided with adjustable stop means, here shown in the nature of screws 40, the heads of which coact with the inner side of the 15 drawer front 14. The screws 40 are particularly convenient to adjust inasmuch as they are accessible from the front of the framework when the drawer is removed.

It will be observed that my construction does 20 not add to the cost of the article of furniture in which it is incorporated. The guide pieces 30, attached in the manner shown in Figures 5 and 6, do not add anything substantial to the cost of the drawer, and the yielding lateral guide 25 strips 18 effect a saving over conventional guide means now in use, for example the center strip guide commonly employed to guide drawers lat-

erally, and in addition thereto considerable time is saved in that it is not necessary for the cabinet maker to make a series of adjustments before the drawer finally operates in a satisfactory manner. This is due to the yielding movement of the guide 5 strips.

What I claim is:

In a furniture construction, the combination of a drawer receiving frame and a drawer slidably mounted therein, said frame including a 10 pair of spaced apart drawer supporting rails, an upper rail arranged above one side member of the drawer, a guide piece formed of wood and being arranged vertically on the inner side of said side member of the drawer adjacent the back 15 member thereof and extending from the bottom member of the drawer upwardly above the upper edge of said side member and engaging said upper rail to maintain the drawer in horizontal position, the grain of said guide piece extending 20 lengthwise thereof and means cooperable with said side member of the drawer and said guide piece to maintain the same in vertical position and to permit vertical expansion and contraction of the side member of the drawer relative to said guide piece. 25

LEOPOLD STICKLEY.
